Primary Examiner — Kelley Donnelly(74) *Attorney, Agent, or Firm* — Shimokaji IP(57) **CLAIM**

The ornamental design for a multifunctional table board, as shown and described.

DESCRIPTION

FIG. 1 is a front view of a multifunctional table board showing my new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof;

FIG. 7 is a first perspective view thereof; and,

FIG. 8 is a second perspective view thereof.

The portion shown in broken lines is for illustrative purposes only and forms no part of the claimed design.
